(57) CLAIM

The ornamental design for a display screen or portion thereof with a graphical user interface for home listing comparisons as shown and described.

DESCRIPTION

The FIGURE is a front view of a display screen or portion thereof with a graphical user interface for home listing comparisons.

The outer perimeter broken lines in the figure depict a display screen or portion thereof and form no part of the claimed design. The remaining broken lines in the figure depict portions of a graphical user interface for home listing comparisons and form no part of the claimed design.
